UNITED STATES PATENT OFFICE.

ANTONI KUCZABOWSKI, OF ST. PAUL, MINNESOTA.

FOLDING CHAIR.

1,231,386.

Specification of Letters Patent. Patented June 26, 1917.

Application filed July 17, 1916. Serial No. 109,720.

To all whom it may concern:

Be it known that I, ANTONI KUCZABOWSKI, a subject of the Czar of Russia, residing at St. Paul, in the county of Ramsey and State 5 of Minnesota, have invented certain new and useful Improvements in Folding Chairs, of which the following is a specification.

This invention relates to new and useful improvements in a folding chair.

10 The primary object of the invention is the provision of a folding adjustable chair especially adapted to be readily carried from place to place for convenient use at such places as picnics and games, the chair affording a comfortable seat when set up in use.

A further object of the device is to provide a chair having a back readily adjusted at a desirable inclination and having resili- 20 ent supports for the seat portion, the structure being compactly foldable for traveling and storage purposes.

A still further object of the invention is the provision of a foldable chair that possesses great strength and serviceability but 25 is easy and inexpensive to manufacture while affording a comfortable seat when set up for use and consuming but little space when folded.

With these general objects in view and 30 others that will appear as the nature of the invention is better understood, the same consists in the novel combination and arrangement of parts hereinafter fully described, illustrated in the accompanying drawings 35 and then claimed.

In the drawings forming a part of this application and in which like designating characters refer to corresponding parts throughout the several views:—

40 Figure 1 is a side elevation of the chair.
Fig. 2 is a rear elevation thereof.

Fig. 3 is a view similar to Fig. 1 with the supporting back adjusted at an inclination.

Fig. 4 is a side elevation of the chair in 45 its operative folded position.

Fig. 5 is an enlarged central vertical sectional view through the device, the legs and back being broken away, and

50 Figs. 6 and 7 are transverse vertical sectional views taken upon line VI—VI and VII—VII respectively of Fig. 1.

The present invention consisting in a foldable chair broadly consists of a substantially square box-shaped frame 10 having 55 the top 11 thereof forming the chair bot-

tom, the said frame being opened at its under side for accommodating four supporting legs 12 resiliently mounted therein, an adjustable back 13 being attached to the bottom 11 by means of hinges 14.

60

An upholstering mattress 15 extends continuously from the forward edge of the bottom 11 to the upper edge of the back 13 thereby forming an easy seat and back rest for the occupant of the chair. Side arms 16 are pivoted at their rear ends as at 17 to the back 13 being pivotally connected by braces 18 with the opposite sides of the frame 10, as at 19 and whereby the arms will readily adjust themselves according to the position 70 assumed by the back 13 when moved upon its hinges 14 whether in an inclined position as illustrated in Fig. 3 or inoperatively folded as shown in Fig. 4 of the drawings.

The hinges 14 are attached to the back 75 and extend through slots 19' in the rear upper edge of the frame 10 and are attached to the lower side of the chair bottom 11 by means of the lower sections 20 of the said hinges which are in the form of straps 21 80 extending forwardly in contact with the bottom 11 to the forward side of the frame 10 and secured to the chair bottom 11 by means of bolts 22, the said straps being preferably extended as at 23 adjacent their 85 rear ends for connecting with an inverted U-shaped bracket 24 transversely secured to the chair bottom 11 by means of bolts 25 and arranged adjacent the rear side of the frame 10.

90

A U-shaped retaining means 26 is provided for securing the chair back 13 in adjusted positions and consists of leaf springs 27 secured, as at 28, to the aforementioned straps 21 and having heads 29 at their rear 95 ends, which heads are connected together by a strap 30. The heads 29 are provided with notches or teeth 31 upon their upper sides adapted to receive depending feet 32 depending beneath the chair back 13 from the 100 hinges 14. Releasing fingers 33 are outwardly carried by the heads 29 freely projecting through side openings 34 in the frame 10 at opposite sides of the latter.

It will be understood from the foregoing 105 description that by pressing downwardly upon the fingers 33, the feet 32 are released from the notches 31 for positioning the feet in the notches desired for giving the preferred inclination to the chair back 13, the 110

resiliency of the springs 27 normally retaining the feet 32 seated within the said notches.

An inverted substantially U-shaped bracket 35 is carried by the chair bottom 11 oppositely arranged with respect to the rear bracket 24 heretofore set forth, while oppositely arranged flat springs 36 are secured between the opposite ends of the said brackets 24 and 35. Angle irons 37 are normally arranged flatly positioned upon the said springs 36 being centrally secured thereto by rivets 38, the said angle irons being thereby supported longitudinally upon the springs 36. The upper angular ends 39 of the chairs legs 12 which are preferably formed of twisted wire are pivotally attached as at 40 to the angle irons 37. A rear angle iron 37' connects the aforementioned side angle irons 37 together and the ends 39 of the front legs being inwardly foldable are prevented from outwardly pivoting by engaging the said angle iron portion 37' forming a stop bar therefor.

The front legs of the chair are inwardly foldable beneath the frame 12 as illustrated in Fig. 4 of the drawings, while the rear legs are similarly folded inwardly preferably over the front legs for retaining the front legs folded, it being noted that the rear legs are provided with a locking wire or tongue 41 which is positionable within a rear notch 42 in the frame 10 when the legs are folded and is removably secured in the said notch by means of a pivoted catch 43, it being noted that the tongue 41 is also provided with a hook 44 at its free end for engaging a cross brace 45 which connects the front legs 12 together.

The chair above described when set up for use provides a comfortable seat by means of the upholstering 15 and the adjustability of the back 13 by means of the fingers 33, while the springs 36 form a resilient mounting for the angle irons 37 to which the legs 12 are pivotally attached thereby giving the suitable cushioning effect to the bottom frame 10. The back 13 and legs 12 are read-

ily folded when desired in a compact manner, as illustrated in Fig. 4 of the drawings. The legs are retained folded by means of the catch 43 while a strap 46 is carried by the back 13 adapted for removable attachment with a stud 47 projecting from the adjacent side of the frame 10 for retaining the back 13 and arm 16 in their folded positions. A strap handle 48 is also arranged upon the frame 10 whereby the folded chair may be readily carried when desired.

While the forms of the invention herein set forth are believed to be of the preferred construction, minor changes may be obviously made without departing from the spirit and scope of the invention as claimed.

What I claim as new is:—

1. A chair comprising a bottom frame open at its under side, opposite inverted U-shaped brackets mounted within the said frame, flat springs secured in parallelism between the opposite ends of the said brackets, a U-shaped angle iron member supported upon the said springs normally positioned in flat longitudinal contact therewith, securing means between the central portions of the said springs and the said angle iron member, and legs carried by the said angle iron member.

2. A chair comprising a bottom frame open at its under side, opposite inverted U-shaped brackets mounted within the said frame, flat springs secured in parallelism between the opposite ends of the said brackets, a U-shaped angle iron member supported upon the said springs normally positioned in flat longitudinal contact therewith, securing means between the central portions of the said springs and the said angle iron member, legs pivoted at their upper ends to the side portions of the said angle iron member within the said frame, the connecting portion of the angle iron member being in abutting engagement with the adjacent legs when the device is operatively positioned.

In testimony whereof I affix my signature.

ANTONI KUCZABOWSKI.
